UNITED STATES PATENT OFFICE.

HARRY H. BLADES, OF DETROIT, MICHIGAN.

REGULATING-SWITCH FOR ELECTRIC MOTORS.

SPECIFICATION forming part of Letters Patent No. 397,773, dated February 12, 1889.

Application filed March 23, 1888. Serial No. 268,222. (No model.)

To all whom it may concern:

Be it known that I, HARRY H. BLADES, a citizen of the United States, residing at Detroit, county of Wayne, State of Michigan, have invented a certain new and useful Improvement in Manipulating-Switches for Electric Motors; and I declare the following to be a full, clear, and exact description of the invention, such as will enable others skilled in the art to which it appertains to make and use the same, reference being had to the accompanying drawings, which form a part of this specification.

My invention relates to certain new and useful improvements in electric switches, and more particularly to that class of switches designed to govern the current which operates an electric motor or other analogous mechanism.

The various features of my invention will be more fully hereinafter described and claimed, reference being had to the accompanying drawings.

The object of my invention is to provide an improved switch of such construction that when actuated by means of a foot-lever or other suitable mechanism current may be admitted to the motor, and by further operation of the same more current may be admitted until the motor has attained its maximum current, when by further movement of the switch this maximum current may be shunted and passed through the armature in the reverse direction, thus exerting its full force to stop or reverse the motion of the motor; or by returning the switch to its normal position simultaneously with the reversal of the current the current may be cut out from the armature and the armature instantly stopped.

In the drawings, Figure 1 is a diagrammatic view of my improved switch and its connection with the motor and the resistance-coils; Fig. 2, a side elevation of the switch, and Fig. 3 a sectional view of the same. Fig. 4 shows the device as applied to a dental motor adapted for operation entirely by hand, and showing by dotted lines how it may be arranged to be operated entirely by the foot.

A represents the base on which the switch is secured; B B', contact-brushes secured to the revolving shell B², which is provided with

a pulley, B³, and spring B⁴; C, the drum or block, upon which are mounted the conducting-segments a b c d and 1, 2, 3, 4, and 5; D and F the field-magnets, and E the armature of any electric motor; G, a resistance-regulator containing coils g g' g² g³, with their respective binding-posts; H, the operating handle or lever.

The operation of my device is as follows: Supposing the parts to be in the positions shown in Fig. 1. It will be seen that the current will pass through the field-magnet D, thence to the binding-post g of the regulator and through the four resistance-coils g, g', g², and g³, thence along the wire k to the segment 1 and through connection l to segment d and the brush B to segment c, and thence through shunt m to segment 5, and out through n and N through the field-magnet F to the main line. This, it will be seen, short-circuits the armature, and the motor remains inactive, with the current passing through the field-magnets and the regulator. Now suppose the operator moves the switch, bringing brush B into contact with segment 1 and the brush B' into contact with segment a, the current will pass, as before, through the resistance-coils to the segment 1, thence through brush B and wire o to armature E and through wire p and brush B' to segment a, and thence through wires n' and N through the field-magnet F. This, it will be seen, brings into the circuit the entire resistance of the regulator, giving the armature its minimum amount of current, and consequently slow speed. Now, to increase the speed, the operator moves the switch so as to bring brush B into contact with segment 2, brush B' being still in contact with segment a. Then the current passes through field-magnet D and three only of the resistance-coils, passing through posts g² and wire j to segment 2, then through brush B and wire c, armature E' and wire p and brush B', and thence through segment a and wire n' and N through field-magnet F, as before. So, also, segments 3 and 4 may be brought into contact by the continued rotation of the brush-holders, and as each successive segment is brought into play one coil of the resistance is cut out, thus giving more current to the armature. Now, to reverse the

armature, the operator brings the switch to the end of its stroke, when brush B will form a contact with segment 5 and B' with segment b. In this condition the current will pass 5 through the field-magnet to binding-post g and wire h to segment 4, thence through shunt r to segment b, whence it is carried by brush B' and wire p to the armature E, thence through wire o and brush B to segment 5, and thence 10 through wires n and N through the field-magnet F. This, it will be observed, will reverse the direction of the current through the armature and give it a reverse motion. This is accomplished while the full current 15 is passing through the motor, and the armature will, when reversed, revolve with its maximum power and speed. Now supposing it is desired to stop the motor suddenly, the operator first reverses the armature, as above, 20 and when it is just coming to a rest simply releases the switch and the spring returns the brush-holder and brushes to the position shown in Fig. 1, thus short-circuiting the armature. This same result may, of course, be 25 accomplished by reversing the polarity of the field-magnets instead of the armature, in which case the connection of the armature will be substituted for the connections with the field-magnets, and vice versa. This is a very 30 desirable feature, as it is often desirable to stop the motor instantly, and without allowing the rapidly-revolving armature to slow up and stop after the current has been cut off, as is the case in all ordinary constructions.

35 By means of this device the operator will have perfect control over the motor and any mechanism operated thereby, and can run the same at a high or low speed, or can reverse the motion instantly, or instantly stop 40 the motor, if desired.

Instead of having the segments connected with resistance-coils, as shown, they may be connected with a series of battery-cells, and the operation of the switch will be to bring 45 into the circuit one, two, or any desired number of cells, thus giving the desired speed to the armature.

Of course the number of segments into which the conductor is divided may be varied 50 to produce any desired graduation of the current and the consequent regulation of the speed of the motor.

In certain systems it is essential, for the proper operation of the current, that a certain resistance be maintained on the line, 55 and in such case the segments c and d are so arranged as to simply short-circuit the armature without cutting out the field-magnets. In some cases this may not be necessary, and 60 in this event the segments c and d may be dispensed with and a blank substituted in their stead. This results in breaking the entire current through the machine.

The switch may be made to be operated 65 either by the hand or by the foot of the operator, and is especially well adapted for use in governing a dental motor. To this end it may

either be located at or near the floor to be operated by the foot, or it might be located on the standard or bracket of the supporting stand and be operated by hand. Its adaptation to a dental motor is illustrated in Fig. 4, the apparatus being adapted for use entirely by hand and showing by dotted lines how it may be adapted for operation entirely by the foot. 70 When the device is thus arranged for a dental motor, the regulator G may be adjusted upon the standard, as shown. This is a very complete and convenient arrangement. The wires leading from the regulator to the switch and 80 motor may be carried within the standard or upon its exterior, as may be preferred. 75

What I claim is—

1. In a manipulating-switch for electric motors, a series of contacts connected and arranged in the order of their operation, as follows: first, contacts adapted to sever the circuit through the motor or short-circuit its armature or field-magnets; second, a series of contacts, each successive one adapted to admit 85 an increased current to the motor; third, contacts adapted to reverse the current through the armature or field-magnets while at its maximum, and, in connection with said switch, means for instantly returning the switch to 90 its starting-point when released, substantially as and for the purposes described.

2. A manipulating-switch for motors, made in the form of a cylinder with segmental contacts and concentric sweep provided with 100 spring-contacts adapted to ride over said segments, and a spring for returning them to the starting-point, said segmental contacts connected and arranged in the order of their operation, as follows: first, contacts adapted to 105 break the circuit through the motor; second, a series of contacts, each successive one adapted to admit increased current to the motor; third, contacts adapted to reverse the current through the armature or field-magnets while at its maximum, substantially as 110 described.

3. The switch consisting of segmental contacts arranged upon a surface of a stationary cylinder, a cylindrical shield surrounding 115 the same and having spring-contacts upon its interior surface adapted to ride over said segments, a spring for retracting the same to its initial position, and a band and treadle whereby motion may be communicated to the 120 switch by the foot of the operator, substantially as described.

4. The combination, with a dental motor, its stand and switch mechanism, of a resistance-regulator, G, the same being in the form 125 of a spool sleeved over the upright of the stand, substantially as described.

In testimony whereof I sign this specification in the presence of two witnesses.
